UNITED STATES PATENT OFFICE.

CAROLINE THORN HOFER, OF NEW YORK, N. Y.

ATTACHMENT FOR HAT-PINS, &c.

SPECIFICATION forming part of Letters Patent No. 779,160, dated January 3, 1905.

Application filed July 1, 1904. Serial No. 214,881.

To all whom it may concern:

Be it known that I, CAROLINE THORN HOFER, a citizen of the United States, residing in the borough of Manhattan, city, county, and State of New York, have invented certain new and useful Improvements in Attachments for Hat-Pins, of which the following is a full, clear, and concise specification.

This invention relates to a new article of manufacture of improved construction adapted to receive and hold the points of pins, needles, or other pointed instruments, whereby the same are retained in position, protected from injury, and protected from doing injury; and more particularly the invention relates to a device of this kind which is capable of ready attachment to the hat-pins of ladies' hats.

Referring to the drawings forming a part hereof, Figure 1 is a side elevation of the device in operation. Fig. 2 is a central longitudinal section thereof. Fig. 3 is a separate view showing the box-sections opened. Fig. 4 is a similar view showing a different style of joint, and Fig. 5 is a modification illustrating the application of the invention to ornamental uses.

It will be seen from the above that the device comprises box or casing sections 1 and 2, which may be united by a screw-thread, Fig. 3, or by means of an ordinary lap-joint, as shown in Fig. 4. Within the box is contained a body of cork or other elastic material, and an aperture is provided in one of the box-sec-

tions through which the point to be protected is inserted into the body of elastic material. 35 According to this invention the aperture is made in the form of a tube 3 with a flaring or funnel-shaped mouth, which tube is suitably attached to the box-section and serves to guide the pin-point through the aperture. 40

In adjusting the device above described to a hat-pin while in use the insertion of the pin is greatly facilitated by reason of the tapered opening.

Having described my invention, what I 45 claim, and desire to secure by United States Letters Patent, is—

As a new and improved article of manufacture, an ornamental pin retainer and guard composed of two box-sections having means 50 for holding them together, a body of elastic material contained within said box-sections, and a tube with a flaring or funnel-shaped mouth secured to an aperture in one of said sections and adapted to guide a pin-point 55 through said box-section into the elastic material, substantially as and for the purpose set forth.

In testimony whereof I have signed my name to this specification in the presence of two sub- 60 scribing witnesses.

CAROLINE THORN HOFER.
